VENTILATOR ATTACHMENT FOR WINDOWS

Robert Washington, New York, N. Y., assignor of
one-fourth to James Edward Hazel, New York,
N. Y.

Application May 13, 1938, Serial No. 207,800

4 Claims. (Cl. 156—33)

This invention relates to new and useful improvements in a ventilator attachment for windows.

The invention has for an object the construction of a very simple and durable attachment which may be mounted upon a window and which will be capable of holding a window shade or curtain or other similar element, while in a drawn position, in various spaced positions from the window itself. With this arrangement a passage will exist through the window and around the sides of the shade or curtain, or similar element, which will serve for ventilation purposes.

Still further the invention proposes to characterize the attachment by a bracket adapted to be mounted upon a window sash or other part of a window and having a pivotally mounted arm and a means for holding said arm in various extended positions to engage against a window shade or curtain or like element to hold it as required.

Still further the invention proposes a novel arrangement and construction of the means for holding the shade so that it may be easily placed into the various positions required.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a window with a ventilator attachment mounted thereon constructed according to this invention.

Fig. 2 is a fragmentary enlarged plan view of the ventilator attachment in Fig. 1.

Fig. 3 is a fragmentary sectional view taken on the line 3—3 of Fig. 2.

Fig. 4 is another fragmentary perspective view of the window sash and ventilator attachment.

Fig. 5 is a fragmentary sectional view on the line 5—5 of Fig. 4.

Fig. 6 is a plan view of the device shown in Fig. 5.

The ventilator attachment for windows, according to this invention, includes a bracket 30 which is mounted upon a window sash 31. This bracket 30 has a projecting central portion 30a and side lugs 30b. It is by these side lugs that the bracket is attached on the sash. An arm 32 is pivotally mounted on the central portion 30a.

This arm consists of a projecting finger 32a

which connects with an arcuate portion 32b engaging against one side of the central portion 30a of the bracket. The arcuate portion 32b continues and connects with a joining portion 32c which extends over the top of the central portion 30a. At the other side it connects with another arcuate portion 32d which in turn terminates in an inwardly directed portion 32e coaxial of the arcuate portions 32b and 32d. The inwardly directed portion 32e extends into an opening formed in the side of the central portion 30a. The arrangement is such that the finger portion 32a may be pivoted upwards and downwards about the portion 32e as a pivot.

The sash 31 constitutes the inner sash of a window construction which also has an outer sash 35. The sashes 31 and 35 are slidably supported in a window frame 36 and upon the top portion of which the roller of a window shade 37 is mounted. The arm 32 is adapted to be extended horizontally with relation to the sashes or vertically along the sashes, as shown by the dot and dash lines in Fig. 3, by merely pivoting it about the central portion 30a of the bracket 30.

A block 33 having a serrated front side is mounted on the central portion 30a and engages against the arcuate portion 32b for resiliently holding the finger 32a in fixed positions. The arrangement is such that the finger 32a may be manually gripped and pulled to disengage the arcuate portion 32b from contacting the serrations of the block 33. It is then possible to pivot the finger portion 32a upwards and downwards about the pivot 32e to various positions. When the finger 32a is released the curved portion 32b will re-engage the serrations of the block 33.

The operation of the device is as follows: The window shade 37 is drawn downwards across the window sashes after one of the sashes has been opened to permit the air to enter the room. The arm 32 is then pivoted to cause its free end to engage against a portion of the window shade 37 for holding the window shade spaced from the frame 36 to form passages for the air at the sides of the shade to permit the room to be better ventilated.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I

claim as new, and desire to secure by United States Letters Patent is:

1. A ventilator attachment for windows, comprising a bracket adapted to be mounted on a window sash, an arm pivotally mounted at one end on said bracket and having a projecting finger adapted to engage a window shade, or curtain or the like to hold the same spaced from the window, and means for holding said arm extended or parallel with said window, including a serrated element concentric with the pivot of said arm and engaging a portion of said arm, and a resilient element maintaining said arm in contact with said serrated element, comprising a portion of said finger and having sufficient inherent resiliency for engaging said serrated element.
2. A ventilator attachment for windows, comprising a bracket for mounting on a window sash, an arm having one of its ends pivotally supported upon said bracket and the other of its ends engageable against a window shade for holding the same spaced from said window, said arm comprising a length of wire consisting of a finger portion having its outer end engageable against said window shade, an arcuate portion continuing from the inner end of said finger portion and engageable against one side of said bracket, a joining portion continuing from said arcuate portion for extending across the faces of said bracket, a second arcuate portion continuing from said joining portion and engageable against the other side of said bracket, and an inwardly directed portion continuing from said second arcuate portion and arranged coaxially of said arcuate portions and engageable into an opening formed in the adjacent side of said bracket for pivotally supporting said arm thereon, and means for holding said arm in various pivoted positions on said bracket.
3. A ventilator attachment for windows, comprising a bracket for mounting on a window sash, an arm having one of its ends pivotally supported upon said bracket and the other of its ends engageable against a window shade for holding the same spaced from said window, said arm comprising a length of wire consisting of a finger portion having its outer end engageable against
4. A ventilator attachment for windows, comprising a bracket for mounting on a window sash, an arm having one of its ends pivotally supported upon said bracket and the other of its ends engageable against a window shade for holding the same spaced from said window, said arm comprising a length of wire consisting of a finger portion having its outer end engageable against said window shade, an arcuate portion continuing from the inner end of said finger portion and engageable against one side of said bracket, a joining portion continuing from said arcuate portion for extending across the faces of said bracket, a second arcuate portion continuing from said joining portion and engageable against the other side of said bracket, and an inwardly directed portion continuing from said second arcuate portion and arranged coaxially of said arcuate portions and engageable into an opening formed in the adjacent side of said bracket for pivotally supporting said arm thereon, and means for holding said arm in various pivoted positions on said bracket, said means comprising a block mounted on the side of said bracket opposed to said opening and having an arcuate side into which said first-mentioned arcuate portion engages, and serrations formed on the adjacent faces of the arcuate side of said block and said first-mentioned arcuate portion.

ROBERT WASHINGTON. 45
